UNITED STATES PATENT AND TRADEMARK OFFICE
CERTIFICATE OF CORRECTION

PATENT NO. : Des. 480,075 S
DATED : September 30, 2003
INVENTOR(S) : Keita Tanaka

Page 1 of 1

It is certified that error appears in the above-identified patent and that said Letters Patent is hereby corrected as shown below:

Title page.

Item [30], **Foreign Application Priority Data**, "October 2, 2000 (JP) 2000-27867" has been removed.

Signed and Sealed this

Ninth Day of March, 2004

JON W. DUDAS
Acting Director of the United States Patent and Trademark Office
